UNITED STATES PATENT OFFICE.

JACOB B. STONER, OF KANSAS CITY, KANSAS, ASSIGNOR TO SAMUEL LAZERUS, OF SHERMAN, TEXAS.

STOCK-CAR.

SPECIFICATION forming part of Letters Patent No. 444,058, dated January 6, 1891.

Application filed January 24, 1890. Serial No. 337,960. (No model.)

To all whom it may concern:

Be it known that I, JACOB B. STONER, a citizen of the United States, residing at Kansas City, in the county of Wyandotte and State of Kansas, have invented certain new and useful Improvements in Stock-Cars; and I do hereby declare that the following is a full, clear, and exact description of the same, such as will enable others to make and use the same, reference being had to the accompanying drawings, forming a part of this specification.

This invention is an improvement upon that shown and described in a former application filed by me in the United States Patent Office upon the 10th day of October, A. D. 1889, Serial No. 326,591; and it has for its object, first, to enable a series of troughs in a stock-car to be extended toward and withdrawn from a position in line with the heads of the stock simultaneously; second, to provide for a vibrating water-trough a self-folding end support; third, to provide a car-door for the entrance of the stock which is capable of being folded and will unfold to close the door-opening in line with the inner surface of the car; fourth, to provide a sliding rear support for a folding car-door when closed; fifth, to enable the vibrating stall-partitions to be released from a horizontally-retained position from either side of the car; sixth, to enable one exterior end portion of a stock-car to be folded in line with the end hay-racks; seventh, to combine a folding exterior end portion of a car with the interior hay-rack.

My invention further consists in the novel construction and combination of parts, which will first be fully described, and specifically pointed out in the claims.

In the drawings, Figure 1 is a view in perspective of the improved stock-car, showing the normal position of the partitions, troughs, and door when the stock is inclosed and the car in motion. Fig. 2 is a plan view of the car, showing the top portion removed and the troughs in a horizontal position and the girdle-bar connected with the troughs. Fig. 3 is an end view of the stock-car, showing the levers for operating the girdle-bar to the troughs and a portion of the end of the car

broken away to show the troughs and folding end supports. Fig. 4 is a detail portion of the top of the car and of one of the vibrating stall-partitions, showing the means for releasing the horizontal retained partition from either side of the car. Fig. 5 is a detail view of the pipe-closing valve in the water-tanks. Fig. 6 is a detail view of one of the vibrating troughs. Fig. 7 is a detail view of portions of the side of the car at the door-opening and showing the folding car-door in a closed position and the sliding rear support. Fig. 8 is an end view of the folding parts of the folding door shown in a folded position and held by the catch. Fig. 9 is a detail view of the water-troughs at the end of the car, showing the folding braces and also the movable end portion of the car connected therewith. Fig. 10 is a detail view of portions of the folding braces to the water-troughs, showing the movable end portion of the car connected therewith. Fig. 11 is an alternate view of the means for operating the folding water-troughs. Fig. 12 is a vertical sectional view of the car, showing the transverse vibrating partition and the catch and its operating-lever in the roof of the car. Fig. 13 is a detail view of a portion of the inner side of the car, showing the vibrating partition and folding hay-rack in section and the connections between the said partition and the folding hay-rack and the wall of the car. Fig. 14 is a detail view of the sliding bar, showing the pivot in the upper end connected with the sliding clasp. Fig. 15 is a detail view of one of the eccentric lugs and a portion of the wall of the car, showing the lug connected with a portion of one of the hay-rack bars and said wall.

In the construction of my improved stock-car, A A represent the longitudinal and B B the transverse floor-beams.

C represents the floor of the car.

D D D D are the standards at each corner of the car.

E E are carlings which support the roof F and are attached to standards D.

D' D' D' D' are the side standards of the car, which correspond in height to standards D D and are grouped in pairs which correspond in position in the transverse direction

and on both sides of the car, as hereinafter described.

Extending around the side and ends of the car from the projecting eaves *f* in a downward direction the proper distance and attached to the outer side of the standards *D D'* is a border-plate *G G'*, which forms part of and incloses portions of the respective sides and ends of the car.

The entire space between the inner walls of the car is separated in a transverse direction into separable compartments or stalls by means of a series of vibrating stall-partitions *H H*, which partitions are suspended in a vertical position, so that the distance lengthwise of the car between each partition and also between the ends of the car and adjacent partitions will be nearly equal, and thereby form a series of stalls of the proper length to afford standing room for the stock, and also to arrange said stock in alignment with the sides of the car.

The partitions *H H* are each composed of a frame consisting of the end strips *h h*, which vibrate near the respective inner side portions of the car and extend in one direction nearly to the carlings *E* beneath the roof *F* in one direction and to a point a short distance above the floor *C* of the car in the other direction and are connected by a transverse rod or bar *h'* at their lower ends.

A similar transverse bar *h''* extends from one strip *h* to the other and is attached at points a considerable distance below the line of the upper ends of said strips.

Between the strips *h h* and attached to the strips *h' h''*, parallel with strips *h h*, is a catch-bar *h³*.

To the respective upper end portions of the strips *h h* are attached the short rods *h⁴ h⁴*, which extend at right angles therefrom through suitable transverse openings in the plates *G G'* on both sides of the car and form the pivots upon which the gates *H H* vibrate.

Upon the exterior side of the plates *G*, beyond which the rods *h⁴ h⁴* extend, are attached at right angles the depending levers *h⁵ h⁵*.

Between the upper bar *h²* of each partition and the strips *h h* in the direction of the roof of the car is arranged the folding hay-rack *I*, the construction of which is similar to that shown and described in my former application, and in this instance the parallel rods *i i*, from which the rack-bars *i' i'* extend to strip *h²* of the partition, are pivoted at their respective ends to the eccentric lugs *i' i'*, which are pivoted to the inner side portions of plates *G G'*. The said rack-bars *i' i'* are connected rigidly at one end with the rods *i i* and provided with a loop at the other end, which extends through the bar *h²* of the partition *H*.

To the side of one of the carlings *E* between the inner sides of the car and above the several vibrating partitions and the strip *h³* of each partition when said partition is in horizontal position a swinging catch *K* is pivoted at one end. The under portion of the lower end of the catch at *k²* is extended in

the line of the width of the car and between the slats *h h* of the partition *H*, and said end portion of the catch *K* is curved, so as to be thrown to one side by and engage with the strip *h³* of the partition *H*. A releasing rod or lever *L* extends across the car in line with carling *E* and is attached to the side portion of the catch *K* below the pivot *k*. The respective end portions *l l* of the rod *L* are bent at right angles and extend nearly to the inner side portions of the plates *G*. Through the said plates *G G'* are made, in line with the end portions *l l* of lever *L*, the transverse openings *g g*, corresponding in number to the levers *L L* and of a sufficient size to admit the hand.

Over the openings *g g* are pivoted a corresponding number of self-closing swinging covers *g' g'*, which prevent sparks from the engine entering the car near the hay.

The plates *G' G'*, which partially inclose and are upon the end portions of the car, are hinged at their lower edge by means of the hinges *dd* to the standards *D D*, the upper portion of which vibrates in an outer direction from the ends of the car. To the lower edge portion of the said plate *G'* are attached rigidly the lower end portions of a series of bars *m m*, which extend upwardly in the direction of the roof of the car and incline inwardly within the car at an angle to the plate *G'*.

Attached in a horizontal position to the upper end portion of the bar *m* is a bar *m'*, which, together with the said bars and the vibrating end plate *G'*, constitutes the hay-rack *M*. A transverse slot *g²* is made through the side of the plate *G'* at a point midway between the sides of the car, extending from the upper edge portion a suitable distance in a downward direction, for the purpose herein-after described.

Extending entirely around the car nearly in line with the beams *A B* and in close proximity thereto is an endless girdle-bar *N*. At each end portion of the car is a bar *O*, which is pivotally attached at the lower end to the girdle-bar *N*, the upper end portion of which extends vertically in line with the slot *g²* in the plate *G'* and to a point in line with the carling *E* at said ends of the car.

Midway between the sides and upon the top of the car is placed a longitudinal plank walk *P*, beneath which are the transverse supporting-blocks *p p*.

Extending the entire length of the car upon its top and beneath the walk *P* is a longitudinal rock-shaft *R*, which extends through the perforations *p p* in the blocks *p p*, and a portion *r* of the ends of said shaft *R* are bent at right angles and extend over the ends of the car and are pivotally attached at *o* to the upper end portion of the bar *O*. To the shaft *R* is attached at a suitable point between opposite ends one end portion of a short operating-lever *r'*, a transverse opening *p²* being made through the walk *P* to permit the vibration of said lever.

The heretofore-described standards D' D' are placed in position corresponding to each other in the transverse direction of the car and a short distance from and upon either 5 side of the line of the transverse partitions H H.

Between the inner side portion of the standards D' D' and on both sides of the vibrating partitions H H, which are nearly opposite, are 10 placed the vibrating or folding troughs S S, which consist of longitudinal water-tight boxes having sides s s, ends s' s', and a bottom portion s². Each one of the troughs S S is comparatively narrow in width and in length 15 extends in a horizontal position nearly one-half the direction of the described width of the car between its sides.

To the girdle-bar N, in line with each of the standards D' D', is rigidly attached a 20 transversely-arranged flat plate n, which extends above the bar N in a vertical direction a distance slightly in excess of the width of the sides of the troughs S S, and is provided with a transverse perforation n' through the 25 upper end portion.

To both sides of each trough S and the end portions s' s' are attached tubular flanges s³ s⁴, which in position are near the line of the opening in the top of said troughs. To the 30 plate n is then pivoted the near end portions s' of the troughs S S in pairs in following manner:

Through the flange on one side s of a single trough is extended one end portion of a rod 35 T, which also extends in the direction of the end portion s' of the trough through flange s⁴, thence bent around the said end portion s' of the trough, and thence within the flange s³ on the other side of the trough, and from the line 40 of the latter flange s³ the said end of the rod T is bent at right angles and extended a distance corresponding to the thickness of the said bars h h of partition H. Thence said rod is extended through the flanges of a 45 trough parallel therewith, forming a rigid connection between said troughs, which are separated by the space of the intervening partitions and extended through the flanges s⁴, thence around the end portion s', and 50 through the respective flange s³ in the other side of the trough, in the line of which flanges s³ s⁴ at right angles to the said troughs are extended short portions t t of the said rod T, which enter the perforations n' in the plates 55 n n on the bar N. A portion of the end s' of each trough is cut away at s⁰ between the sides a short distance below the line of the opening in the said troughs, so as to afford an overflow.

60 Extending a short distance beyond the side s s of each one of the troughs in line with the bottom s² is attached in a transverse direction the pivot s⁵. To the end portions of the pivot s⁵ on each side of the single troughs is pivoted one end portion of a supporting-brace s⁶ s⁶, the other end portion of which extends from the pivot s⁵ to the lower end portions of the

standards D' D' on the side in line with trough S and are pivoted to said standards at s⁷ near the line of the floor C.

70

At the ends of the car between the corner standards D D are the troughs S' S', which extend in the transverse direction of the car, between the adjacent ends of which is a wide space s⁸, in which the bar O is permitted to 75 vibrate. The troughs S' S' are supported when in a horizontal position and are provided with similar braces as are made for the troughs S S on the side of the car, and said troughs are also pivotally connected with the 80 bar N by means of lug n', which is similar to the lug n on the bar N. The braces s⁹ s⁹, however, for the end troughs S' S' are made correspondingly shorter than the braces s⁶ on the 85 side of the car, and through the lugs n' n' are made longitudinal slots n² n² to receive the pivots t t on the ends of troughs S' S'.

To the braces s⁹ s⁹ and upon the side of each trough S' in the direction of the interior of the car are the end closing portions or walls 90 s¹⁰ s¹⁰, which extend from the floor C of the car to within a short distance of the upper end portions of the brace s⁹ s⁹ in one direction and from one brace s⁹ on a trough S' to the other in the transverse direction of the 95 car. On the respective end portions of the walls s¹⁰ are secured loosely the clasps s¹¹, which extend around the braces s⁹ s⁹ and permit the vertical adjustment of said walls thereon.

100

The entrance for the stock is on the side and near each end portion of the car, and a suitable distance from the corner standards D in the direction of the other end of the car to give proper entry room is secured to the 105 beam A and also to the roof of the car in a vertical direction a door-jamb or post D², the portion of the plate G covering partially the door-opening and said posts D D² being removed.

110

Between the standards D at the corner of the car and the post D² is placed a vertically-folding door V. Said door consists of a series of horizontal slats v v', which are shorter in length than the width of the door opening, 115 one of which slats is pivoted at each end in a horizontal position near the line of its upper horizontal edge at a point near the roof of the car and to the respective side portions of the standard D and jamb D², also at a point 120 near the line of the inner wall of the car. To the lower horizontal edge portions of the said slat v is then hinged the upper horizontal edge portion of another slat v', and in the order as described are hinged a sufficient 125 number of slats v v' to extend to the floor C. In the portions of the jamb D² and the standard D forming the other jamb to the door-opening is made a vertical slot v², in which are inserted the alternate pivots v³, which 130 join two of the slats in series and extend beyond the end portion of said slats.

To the upper end and outer side portions of the standard D and the jamb D² is attached

a horizontal guide-bar v^4 , upon and extending around which is a sliding clasp or plate v^5 . To the plate v^5 , beneath the bar v^4 , is pivoted the upper end portion of a sliding bar v^6 , which extends in width from the outer side portion of the ear to a point in line vertically with the inner side portions of the slats v^v' , when the slats are also in a vertical line, and also flatwise slides past ends of the slats v^v' over jamb D^2 . On the beam of the car, extending across the opening and outside of and in line with the lower end portions of the bar v^6 , is a narrow guide-strip v^7 . Upon the lower end portion of the bar v^6 is secured a push-bolt v^8 . Through the slot v^7 and extending into the beam A of the car is made the perforation v^9 , which receives the bolt v^8 . To the inner side portion of the bar v^4 is pivoted the upper end portion of a vibrating catch or hook v^8 , which extends in a downward direction a suitable distance to engage with the lower slat when the series of slats are in a folded position.

Upon the roof of the car are two parallel feed and water tanks W W, each one of which is divided in a longitudinal direction by the vertical partition w into two separate compartments $w^2 w^3$, the outer compartment w^2 being water-tight. The said tanks W extend in width nearly to the eaves of the car in one direction and to within a short distance of the plank walk P in the other, and in a longitudinal direction is comparatively shorter than the top of said car.

From the water-tank w^2 extends a suitable number of flexible water-conductors w^4 in line with the respective troughs S S on the side of the car, and at the end portion of the car are similar conductors, which extend from the end portion of the water-tanks in a downward direction to the folding troughs S' S'.

Upon the inner side portion of each tank, covering the openings to the conductors w^4 , is a series of valves $w^5 w^5$, which are connected to a rod w^6 , which passes lengthwise through the tanks w^2 in line therewith.

On the roof of the car in a transverse direction beneath rod R and near the end portions of the feed and water tanks W W is the rock-bar w^7 , which is held by the staples w^8 to the top of the car and rotates thereon. The end portions of the bar w^7 are bent at right angles to its line of direction and are pivotally connected with the end portion of rod w^6 , which extends in an inclined direction from the top of the car through the end portion of said tanks near the top.

For supplying the troughs S' S' at the end of the car a flexible pipe w^9 extends from the end portion of each trough w^2 over the end portion of the car in line with one of the corner standards D.

To the rock-bar w^8 is attached an arm w^{10} , which extends from the radius of the bar at a different angle from that of the arm $w^7 w^7$.

Through the top of the car, and also the bottom portion of the feed-receptacle $w^3 w^3$,

are made the rectangular-shaped vertical openings $w^{12} w^{12}$, which are in line with and over the hay-racks I.

To the inner sides of the standards D D, which are on the sides of troughs S S and forming the inner walls to the ear, are attached the horizontal bars $d^x d^x$, which are separated the proper distance apart for light and ventilation.

In the admission of stock in any improved car the bar v^6 , which is at right angles to the slats v^v' , is turned upon its pivot flatwise in relation to said slats, and the bar slides along the guide-bar v^4 toward and close against the outer side portion of the jamb D^2 . The lower slat v' is then lifted in a vertical direction and the series of slats fold one upon another, and near the top of the car the catch v^8 slips beneath the lower longitudinal slats and retains the parts in the folded position.

In the present invention the stock are transported in the same manner as shown and described in the former application—that is, in line with the sides of the car—and before the admission of the stock the partitions H H are raised in a horizontal position, the lower ends describing a circle and the partition folded within the roof of the car and secured by the self-fastening catch K. The drove of stock is then admitted in numbers such as to conveniently occupy a single compartment between two transverse partitions H H, or between a partition adjacent to the end of the car, and this being accomplished the slides g' on the plates G are pushed one side and the hand passed through one of the openings g , which conceals the rods L, and the bent portion l seized and moved in the direction of the plate G, and the catch K is released, which permits one of the stock-inclosing gates in the series to which the catch K corresponds to fall in a vertical position, and in which position they are secured, as I have more fully described in a former application. The stock having been admitted to the fill of the car and each partition dropped in position to complete the stalls, the catch v^8 is released on the side of the car, and the slats v^v' of the door fall in a vertical position and in line with the inner side portions of the wall of the car, so that the cattle are protected from injury when rubbing against the said walls. The vertical brace-bar v^6 is then moved in its slide to a position midway between the jamb D^2 and the standard D and turned on its pivot and in a position at right angles to the slats v^v' , and the slats, by means of the brace-bar v^6 , are able to resist violent pressure. In their normal position the water-troughs S S' are in a vertical position, as seen in Fig. 1. When it is desired to water the stock, the lever r' upon the top of the car is thrown from a horizontal position nearly the distance described in a half-circle into the position seen in dotted lines, the rock-shaft R is rotated, and the bar O is elevated, which elevates the girdle-bar N, and the adjacent end

125

130

portions of all the troughs are raised simultaneously the proper height in horizontal position, the troughs S S extending in the transverse direction of the car on both sides of the 5 intermediate stall-gates H H, so that a portion of the stock in each compartment or stall may be reversed in position, and thus prevent the horns of the cattle from interfering with each other. Water is then admitted to 10 the troughs S S' through the respective water-conductors w⁴ w⁴ from the water-tank w², and as the supply of water fills the troughs the surplus runs over the end portion s^x in the space s⁰ outside of the car, thus preventing 15 an overflow within the car. The reversal of the position of the lever r' then throws the troughs simultaneously in a vertical position, and the remaining quantity of water in the bottom of the troughs is dumped over the 20 end and outside of the car.

Instead of a girdle-bar, as seen in Fig. 1, I may use other means of operating the troughs, as seen in Fig. 11. In this latter figure sprocket-wheels are connected with the operating-shaft on the top of the car, and also with the pivots of the rods on the folding-troughs, and extending from the sprocket-wheel on the 25 rock-shaft R to the sprocket-wheel on the pivot of the respective troughs is a sprocket-chain r², the line of travel over the eaves of 30 the car being facilitated by the guide-wheels at the eaves.

The dry feed for the cattle is fed through the openings w¹² in the roof of the car to the 35 hay-racks, which fold and unfold as the gates H H are alternately raised and lowered from a horizontal position, as shown in the former application. At the end of the car, however, the closing end portion of the wall of the car, 40 which forms part of the hay-rack, is vibrated in an outward direction, the slot g² permitting the said end portion to pass the bar O, which, in either of the two positions of the bar N, is in line with said slot. The hay is then introduced to the hay-rack G' from either the 45 top of the car or the ground, as preferred. The vibration of the hay-racks at the end of the car also enables the entrance of the cattle to be made clear and not standing in the way 50 of the horns of the stock, and combined with the closed end or wall of the car is a guard from fire. Should it become necessary to convert the car to other uses, such as lumber, iron, &c., the adjustable end walls of the car are 55 lifted a sufficient height to admit material of different lengths in the longitudinal direction of and within the car.

Having fully described my invention, what I now claim as new, and desire to secure by Letters Patent, is—

1. In a stock-car having suitable compartments for the stock and transverse openings in the walls of said car, the combination, with 60 transverse vibrating stall-partitions having end strips suspended at their upper ends from the inner top portion of said car, of a

self-acting catch in said inner top portion of said car, engaging with the vibrating end portion of said partition, a releasing-lever connected with the said catch, having its end extending to the transverse openings in the walls of said car, and self-closing covers on said car over said transverse openings, substantially as and for the purpose described. 70

2. In stock - cars having folding water-troughs and a brace pivotally attached to and supporting the inner end portion of each trough, the combination of a vertically-sliding girdle-bar extending around said car and having suitable elevating-levers connected 80 with said bar on the car, and supporting-plates on said girdle-bar pivotally connected with the outer end portion of said troughs, substantially as described. 75

3. In stock - cars having folding water-troughs and a brace pivotally attached to and supporting the inner end portion of each trough, the combination, with a vertically-sliding girdle-bar extending around said car, having suitable supporting-plates pivotally 90 connected with the outer end portion of said troughs, of a rock-shaft on said car and rods connected with said girdle-bar and said shaft, substantially as and for the purpose described. 85

4. In stock - cars having folding water-troughs, the combination, with said troughs, of a girdle-bar extending around said car, having supporting-plates pivotally connected with the outer end portion of said troughs, trough - elevating devices on said car connected with said girdle-bar, and hinged folding supports at the other end of said troughs, substantially as described. 95

5. In stock - cars having folding water-troughs, the combination, with said troughs, 105 of a girdle-bar extending around said car, having supporting-plates pivotally connected with the outer end portion of said troughs, folding braces at the other end of said troughs, and a rock-shaft on said car, having arms 110 and a rod connected with said arms and said girdle-bar, for the purpose described. 100

6. In stock-cars having an opening in the walls for the entrance of the stock and vertical door-jambs provided with a vertical slot 115 therein, the combination of a folding door consisting of a series of slats hinged together and having pivots in alternate slats arranged in the slots in said door-jambs, for the purpose described. 120

7. In stock-cars having an opening in the walls for the entrance of the stock, a folding door therefor consisting of a series of slats hinged together and adapted to unfold in line with the inner walls of the car, an overhead 125 guide and a slide therein, and a vertical bar pivoted to said slide at one end and suitably braced at the other, for the purpose described. 120
